UNITED STATES PATENT OFFICE.

PETER PAPPAS, OF KANKAKEE, ILLINOIS.

CLOSURE.

1,418,201.

Specification of Letters Patent. Patented May 30, 1922.

Application filed October 29, 1921. Serial No. 511,262.

To all whom it may concern:

Be it known that I, PETER PAPPAS, a citizen of the United States, residing at No. 369 West Merchant Street, in the city of 5 Kankakee, in the county of Kankakee and State of Illinois, have invented new and useful Improvements in Closures, of which the following is a specification.

My invention relates to closures and more 10 particularly to a drain attachment for cabinet and other closures.

An important object of the invention is to provide a means whereby water, dirt and other foreign matter may be effectually prevented from entering the cabinet and dripping upon the contents thereof when the top 15 surface is washed.

A further object of the invention is to furnish a device of the above mentioned character which is neat and attractive in appearance, highly efficient in use and which may be cheaply manufactured.

These and other objects are attained by means of a novel combination and arrangement of parts to be hereinafter described and claimed and in order that the same may be better understood, reference is had to the accompanying drawing forming a part of this specification and in which the invention 25 is shown applied to an ice cream cabinet.

In the drawing,

Figure 1 is a cross-section of an ice cream cabinet showing my invention applied to the closure thereof;

Fig. 2 is a plan view of a portion of a cabinet top with the lid open, showing the application of the invention, and

Fig. 3 is a perspective view of the drain attachment removed.

Referring specifically to the drawing, wherein like reference characters designate like parts throughout the several views, 5 denotes an ice-cream cabinet having a top 6 and holding an ice-cream can 7. I have illustrated a cabinet holding only one can but the invention is adaptable to all types of ice-cream cabinets holding a plurality of cans such as are used in soda fountains and stores. The cabinet itself forms no part of the present invention and therefore will not be described in detail. The lid 6 has an annular opening 8 located above the ice-cream can 7, and this opening may be provided with a hinged cover 9 although any other 55 desired type of cover may be used. The opening 8 has fitted therein at its under face,

an annular ring 10 having an integral up-standing flange 11, the said ring being L-shaped in cross-section. The ring 10 may be fitted to the under face of the cabinet top 6 in any approved manner but I have illustrated it as being attached by means of screws 12 passing through holes 12^a in the edge of the ring and entering the cabinet top 6 as clearly shown in Fig. 1. A rubber 65 gasket 13 is provided to insure a tight fit, thus preventing any leakage. A drain pipe 14 is shown attached to the ring 10 for draining off any water, grease, etc., which may have seeped under the cover 9 and into 70 the gutter formed by the ring 10 and the wall of the opening 8.

From the foregoing it will be seen that I have provided a device which is readily adaptable to ice-cream cabinet closures and 75 to all other closures having an opening therein and a lid or cover for such opening. My invention permits the washing of the top of the cabinet without danger of soapy water, dirt or grease, getting into the ice- 80 cream can. The diameter of the upturned flange 11 of the ring 10 is slightly less than that of the opening 8 so that all drippings that get under the cover 9 will be caught by the ring 10 and conveyed through the drain 85 tube 14 to the ice compartment of the cabinet. The ring 10 takes up only a very little space in the opening 8 of the top 6 and does not interfere with the dipping out of ice- 90 cream from the can 7.

While I have described the preferred embodiment of my invention it will be understood that it is capable of many changes and modifications within the spirit and scope of the appended claims.

I claim:

1. The combination with a closure having an opening therein and a cover therefor; of a gutter attachment in said opening.
2. The combination with a closure having an opening therein and a cover therefor; of a gutter attachment in said opening and means for securing said gutter attachment in the opening.
3. The combination with a closure having an opening therein and a cover therefor; of a gutter attachment in said opening and a drain for said gutter attachment.
4. The combination with a closure having an opening therein and a cover therefor; of a gutter attachment in said opening, means for securing said gutter attachment in said

opening and a drain for the gutter attachment.

5. The combination with a closure having an opening therein and a cover therefor; of an annular ring substantially L-shaped in cross-section and forming with the wall of the opening a gutter around the edge of the

opening; means for securing the ring in the opening and a drain for said ring.

In testimony whereof I affix my signature. 10
PETER PAPPAS.
